(57) **CLAIM**

The ornamental design for a bag, as shown and described.

DESCRIPTION

FIG. 1 is a perspective front view of a bag as worn by person;
FIG. 2 is a front elevation view of the bag;

FIG. 3 is a rear elevation view of the bag;

FIG. 4 is a left Side elevation view of the bag;

FIG. 5 is a right Side elevation view of the bag;

FIG. 6 is a top elevation view of the bag;

FIG. 7 is a bottom elevation view of the bag; and,

FIG. 8 is a front elevation view of the bag with flaps in open position.

The broken lines showing a human figure is included for the purpose of illustrating environmental structure and forms no part of the claimed design.
